W. E. PRESCOTT.
COOLING APPARATUS.
APPLICATION FILED DEC. 7, 1921.

1,427,018.

Patented Aug. 22, 1922.

Inventor

William Edward Prescott
Attorney *R. H. Adams*

UNITED STATES PATENT OFFICE.

WILLIAM EDWARD PRESCOTT, OF LONDON, ENGLAND, ASSIGNOR TO JOSEPH BAKER,
SONS AND PERKINS, LIMITED, OF WILLESDEN JUNCTION, LONDON, ENGLAND.

COOLING APPARATUS.

1,427,018.

Specification of Letters Patent. Patented Aug. 22, 1922.

Application filed December 7, 1921. Serial No. 520,669.

To all whom it may concern:

Be it known that I, WILLIAM EDWARD PRESCOTT, of London, England, have invented certain new and useful Improvements 5 in Cooling Apparatus, of which the following is a specification.

This invention relates to apparatus for cooling liquids, semi-liquids and the like, such as sugar syrups and similar substances, 10 particularly for use in the manufacture of confectionery, and also for cooling fats and substances such as boot polishes, etc.

In the specification of English Letters Patent No. 13602, A. D. 1914, there is disclosed a structure for evaporating and concentrating liquids under the action of a fluid heating medium in which the liquid is forced through a spiral passage of gradually increasing area formed by a spiral 20 plate interposed between two tubes, the outer of which is contained within a steam jacket and the inner of which serves as an outlet for the vapour or steam from the liquid under treatment.

Now the present invention provides an apparatus based on substantially the same principle as the above with, however, certain modifications rendering it particularly suitable for the cooling of liquids, semi-30 liquids and the like as above stated, and in an embodiment of the invention, the spiral passage produced as previously mentioned is adopted, located between inner and outer tubes, the outer of which is enclosed in a 35 jacket for an exterior cooling medium such as water circulation.

The inner tube is, however, closed at its base and into the same leads a supply also for cooling medium such as cold water under pressure, the same being suitably admitted by a pipe at the top extending nearly to the base of the tube and circulating under pressure therein in a direction opposite to that of the material under treatment and 40 discharged also at the top. By such a construction the liquid or semi-liquid passing down the spiral plate may be efficiently cooled from both the outside and inside of the passage through which it passes and is 45 discharged at the bottom of said passage as in the specification above referred to or by other appropriate means.

Cooling apparatus as above described may with advantage be used in conjunction 50 with an evaporating or concentrating ap-

paratus as disclosed in the aforesaid specification in the manufacture of certain confectionery or other goods which first require to be concentrated and then cooled, the two apparatus being coupled together and the 60 concentrated liquid pumped or otherwise fed to the top of the cooler after it leaves the bottom of the concentrator. This connection may take the form of a hopper to receive the concentrated liquid and adjacent thereto a pump with pipe connection to the top of the cooler, but may however be so arranged or constructed as to be swung aside when cooling is not required so that the material from the concentrator may 70 pass directly to a receiving member such as a table to be dealt with according to will.

An embodiment of the invention shown as combined with evaporating or concentrating apparatus of the type previously 75 referred to is illustrated in the accompanying drawings in which Fig. 1 is a vertical section of the combined apparatus and Fig. 2 an elevation from the left hand side of Fig. 1 with certain parts removed.

In said drawings A designates the evaporating or concentrating apparatus constructed substantially in accordance with the invention disclosed in the aforesaid specification No. 13602 A. D. 1914 and comprising an outer casing or jacket *a* containing two tubes *a*¹ and *a*² shown as slightly tapering in relation to each other, (or may be parallel tubes for some substances) and between which is disposed a helically wound 80 or spiral plate *b*, the inner tube *a*² open at the bottom and leading to a vapour outlet to atmosphere at the top at *b*¹ and the outer tube *a*¹ terminating below in a delivery nozzle *b*². The syrup to be evaporated is passed 85 as from a pump through a pipe *c* to the top *c*¹ of the space between the tubes *a*¹ and *a*² to the spiral plate *b* being pre-heated by passing through a tube *d* having inlet *d*¹ and outlet *d*² for steam, whilst the jacket *a* is provided with steam having inlet at *e* and outlet at *e*¹, a pressure gauge *e*² being provided on the outside of the jacket as shown.

To now turn to the cooling apparatus designated by B this is constructed on very 105 similar lines to the evaporating or concentrating apparatus A and comprises the jacket *f* containing the two tubes *f*¹ and *f*² between which is disposed the helically wound or spiral plate *g*. The inner tube *f*² 110

is however closed at the base as shown at f^3 and a cooling medium as cold water is let in to near the bottom thereof by means of a pipe h this water having outlet at the top at h^1 . Cooling medium as cold water is admitted to the lower part of the jacket f by a pipe i and after circulating therethrough is drawn off at the top at i^1 .

The syrup to be cooled is fed to the top of the spiral plate g by a pipe j from any suitable source but in the embodiment shown it is assumed that said syrup has been previously treated in the concentrator A and consequently the syrup from delivery nozzle b^2 of the concentrator is passed into a pump C shown as of the drum type by which it is raised through said pipe j as stated. The cooled syrup is delivered from the cooler B through a delivery nozzle j^4 at the base of the outer tube f^1 .

What I claim as my invention and desire to secure by Letters Patent of the United States is:—

1. A cooling apparatus of the character described comprising an outer jacket, two tubes contained within the jacket and having a spiral passage therebetween, the inner of said tubes being closed at its bottom and

the outer being spaced from the jacket, means for admitting the substance under treatment to the spiral passage, means for admitting a cooling medium to the space between the jacket and outer tube, and means for admitting a cooling medium to the inner tube.

2. A cooling apparatus of the character described comprising an outer jacket, two tubes contained within the jacket and having a spiral passage therebetween, the inner of said tubes being closed at its bottom and the outer of said tubes being spaced from the jacket, means for admitting the substance under treatment to the spiral passage, and means for admitting a cooling medium to the space between the jacket and outer tube and to the inner tube and circulating the same in a direction opposite to that of the substance under treatment.

In witness whereof I have signed this specification in the presence of two witnesses.

WILLIAM EDWARD PRESCOTT.
